Attorneys.

UNITED STATES PATENT OFFICE.

ROYCE L. BEERS, OF DETROIT, MICHIGAN.

HEAT RADIATOR.

Application filed June 12, 1922. Serial No. 567,671.

To all whom it may concern:

Be it known that I, ROYCE L. BEERS, a citizen of the United States of America, residing at Detroit, in the county of Wayne 5 and State of Michigan, have invented certain new and useful Improvements in Heat Radiators, of which the following is a specification, reference being had therein to the accompanying drawings.

10 This invention relates to heaters and relates more particularly to heaters employing the waste combustion gases from a furnace or the like.

15 It is the object of the invention to provide a heater utilizing waste combustion gases and formed with ribs increasing the heating surface.

20 A further object of the invention is to provide a heater having its outlet formed in a plate adapted to occupy various positions according to the location of the chimney to which said opening is to be connected.

25 The invention further consists in the formation of the heater from sections permitting manufacture in various sizes.

In the drawings:—

Figure 1 is a view sectionally showing a portion of a building in which the improved heater is installed and showing the connections of the heater respectively to a furnace and a chimney;

Figure 2 is an enlarged rear view of the heater;

Figure 3 is a cross section view thereof, taken on line 3—3 of Figure 2;

Figure 4 is a view similar to Figure 1 but disclosing an alternative form of the invention.

30 In these views the reference character A designates a furnace and B the usual smoke pipe leading from said furnace to a chimney C. The improved heater which is installed on a floor D above the basement containing said furnace comprises a pair of complementary shell members E either cast or pressed, said members being formed with marginal flanges F which are bolted together, as indicated at G in the central plane of the heater. H indicates vertically extending corrugations formed upon the front of the heater and upon the upper and lower por-

tions of its back, said corrugations increasing the heat dissipating surface and further giving the effect of the coils of a hot water or steam radiator. An inlet opening I is 55 formed in the bottom of the heater jointly in the front and rear members thereof, said opening being surrounded by a collar I' for engagement by a suitable pipe. The back section of the radiator is formed at 60 an intermediate height with a rectangular opening J, the corrugations H being terminated short of said opening. K and L designate two plates which are adapted to jointly close the opening J, one of said plates being 65 formed with the discharge orifice M marginal to which a suitable collar M' is formed for engagement by the discharge pipe. By thus providing the outlet M in one of the two plates K and L, said outlet may be 70 located adjacent either end of the heater or centrally of the back thereof, such an adjustment being effected by simply changing the relation in which the plates K and L are secured to the rear shell of the heater. 75

In order to adapt the described heater to be made in various sizes employing standard sections it is preferred to form both front and rear shells in several sections, the number of which may be increased or diminished 80 according to the desired capacity of heater. Thus in the drawings each of said shells is shown as comprising three sections which are interiorly ribbed, as indicated at N, said ribs being engaged by bolts O rigidly connecting said sections to form the shells. A pipe leading to the described heater from the smoke pipe B is indicated at R and S and S' indicate dampers provided respectively in the pipes R and B for controlling 85 the alternative flow of the combustion gases either direct to the chimney or through the heater.

T designates a baffle horizontally mounted intermediate the inlet and outlet of the casing, marginally extending in close proximity to the side walls and spaced unequally from the end walls of said casing, so as to form a main passage U for the combustion gases at one end of the baffle, a relatively 90 small passage U' at the other end and a plurality of still smaller passages U² ad-

5 jacent the side edges of the baffle within the corrugations of the shell members E. Said baffle may be turned end for end so that the main passage U may be arranged always adjacent the end wall of the casing remote from the outlet, or if the latter is centrally positioned the baffle may be similarly arranged thus forming upward passages of equal size at the ends of the casing. The 10 baffle is held in position preferably by bolts V transversely passing through the shell walls and engaging upturned flanges W along the side edges of the baffle.

15 By allowing a portion of the gases to rise past the baffle flowing through the corrugations of the shells E, a considerable transfer of heat to the corrugations adjacent the passages U² will be insured.

20 The construction shown in Figure 4 is similar to that above described except for the fact that the outlet connection from the heater to the chimney is not established within the room in which the heater is located. Such connection is avoided by providing the pipe fitting X which extends through the floor to the furnace smoke pipe X' with a vertical partition X² forming within said fitting upward and downward 25 passages Y and Y'. A vertical baffle plate Y² within the heater registers with the partition X² forming a continuation thereof, said baffle extending to the upper portion of the heater and abutting the horizontal baffle plate Y³ which is spaced from the 30 ends of the heater to form upward and downward passages. Preferably the partition X² terminates at its lower end in a deflector member Z comprising a bottom wall substantially in alignment with the top 35 wall of the smoke pipe X' and side walls respectively conforming to the curvature of the lower ends of the passages Y and Y'. Below said deflector is arranged a damper Z' adapted to more or less obstruct the 40 smoke pipe X' to deflect more or less of the combustion gases through the heater.

45 As is indicated by the arrows in Figure 4, the combustion gases upon encountering the deflector Z will tend to rise through the passage Y circulating within the heater around the baffles Y² and Y³ finally discharging from the heater through the passage Y'. It is to be observed that even when the damper Z is fully open a certain proportion of the gases will tend to 50 flow through the heater due to the use of the deflector Z.

55 While heating devices have heretofore been employed utilizing waste combustion gases, the same have failed to come into common use largely because of their unattractive and awkward appearance and their lack of compactness. This objection is overcome in the present invention by giving 60 the heater the appearance of a type

of radiator in common use and by adapting it to occupy a space no greater than that required for said commonly used radiator.

65 It is a highly desirable feature of the described heater that it utilizes heat which is otherwise wasted and consequently it may be installed without a resulting increase in fuel expense.

70 What I claim as my invention is:—

75 1. A heater comprising a casing having an inlet for combustion gases and having an opening, and a closure for said opening provided with an outlet for combustion gases, said closure being variable in its mounting upon the casing to vary the location of said outlet with respect to the ends of the casing.

80 2. A heater comprising a casing, having an inlet in its lower portion and having its back formed with an opening elongated from end to end of the casing, and a plurality of plates jointly forming a closure for said opening, one of said plates having an outlet for combustion gases, said plates being attachable to the casing in various 85 relations to each other and to the casing to vary the location of said outlet with respect to the casing ends.

90 3. A heater comprising a casing formed, of a pair of complementary shell members secured together in substantially the central plane of the heater, inlet and outlet openings for combustion gases being formed respectively in the lower and upper portion of said casing.

95 4. A heater comprising a pair of complementary shell members jointly forming a casing and formed with marginal flanges meeting in substantially the center plane of said casing, and fastenings connecting said flanges, the bottom of the casing having an inlet opening for combustion gases jointly formed in the two shell members, and an outlet for such gases being formed in the upper portion of one of said members.

100 5. A heater comprising a pair of complementary shell members forming a casing, one of said shell members comprising a plurality of sections, said sections having inwardly extending ribs, fastenings engaging said ribs for connecting said sections internally of the casing, and fastenings connecting the two shell members externally of the casing.

105 6. A heater comprising a casing having an inlet and an outlet for combustion gases, and having provision for varying the location of said outlet with respect to the ends of the casing and a baffle member within said casing intermediate said inlet and outlet and adjustable relative to the casing ends to correspond with the selected location of said opening.

110 7. A heater comprising a casing having

an inlet and an outlet for combustion gases, said casing having a wall corrugated to increase heat dissipation, and a baffle member within said casing between said inlet and outlet and extending from one wall of said casing transversely to said corrugations, passages for the combustion gases

past the margins of the baffle being formed by the corrugations of the heater, said baffle member being spaced from the other 10 walls of said casing.

In testimony whereof I affix my signature.

ROYCE L. BEERS.
